CPC F16M 11/105; F16M 11/10; F16M 11/048;
F16M 11/12; F16M 13/022

The ornamental design for support for computer terminals and computer keyboards, as shown and described.

See application file for complete search history.

DESCRIPTION

(56) **References Cited**

FIG. 1 is a rear elevation view of a support for computer terminals and computer keyboards showing my new design; FIG. 2 is a left side elevation view thereof; FIG. 3 is a right side elevation view thereof; FIG. 4 is a front elevation view thereof; FIG. 5 is a bottom plan view thereof; FIG. 6 is a top plan view thereof; and, FIG. 7 is a top perspective view thereof. The outermost broken lines immediately adjacent the shaded areas depict the bounds of the claimed design, while all other broken lines are directed to environment. The broken lines form no part of the claimed design.
